UNITED STATES PATENT OFFICE.

CHARLES C. BISHOP, OF ST. LOUIS, MISSOURI, ASSIGNOR OF ONE-THIRD
TO WILLIAM L. RYAN, OF ST. LOUIS, MISSOURI.

TALKING-CLOCK.

No. 830,200.

Specification of Letters Patent.

Patented Sept. 4, 1906.

Application filed March 18, 1905. Serial No. 250,831.

To all whom it may concern:

Be it known that I, CHARLES C. BISHOP, a citizen of the United States, residing at St. Louis, in the State of Missouri, have invented 5 certain new and useful Improvements in Talking-Clocks, of which the following is a specification, reference being had therein to the accompanying drawings.

This invention relates to improvements in 10 talking-clocks, and has for its object the provision of an apparatus of this character which will have the fewest possible operating parts, thereby simplifying the adjustment and operation thereof.

15 A convenient embodiment of the invention embraces a clock of the ordinary type preferably though not necessarily provided with a striking-train, controlling mechanism actuated by the clock at predetermined 20 intervals, and means operatively associated with the braking device of a talking-machine, such as the ordinary phonograph, governed by said controlling mechanism to permit normal actuation of the talking-machine motor, whereby said machine will, 25 through the medium of its record and reproducer, announce the time indicated by the hands of the clock or such other matter as may be desired.

30 The invention also contemplates the complete housing of all of the foregoing mechanism within the clock-casing without necessitating any perceptible enlargement or dis- 35 figuration of said casing, and also the pro- vision of a separate dust-proof chamber, within which is located and inclosed the whole of the talking-machine structure, save only the open end or outer portion of the horn thereof.

40 Novel details in the construction and arrangement of the several parts of the apparatus will be apparent from the detailed description hereinafter given when read in connection with the accompanying drawings, 45 forming part hereof, and wherein the above-referred-to embodiment of the invention is illustrated. It is to be understood, however, that the invention is susceptible of still other embodiments and also that the de- 50 tails herein may be altered or supplanted by others without departing from the spirit of the invention.

In the drawings, Figure 1 is a front eleva-

tion of a clock, the relative positioning of the talking-machine feature thereof being indicated by dotted lines. Fig. 2 is a similar view, the fore part of the clock-casing being broken away. Fig. 3 is an enlarged detail elevation. Fig. 3^a is a fragmentary vertical sectional view on the line $z-z$ of Fig. 2, and Fig. 4 is a detail perspective view.

Referring more specifically to the drawings, wherein like reference characters refer to corresponding parts in the several views, A designates the clockworks, and B an ornamental casing therefor, including a base b and glass front b'.

C is a substantially dust-proof chamber formed by the surrounding walls of the base b and a horizontal partition D, separating said chamber from the clockworks-chamber a directly thereabove. Within this dust-proof chamber I mount a talking-machine of any type desirable for the purpose, said machine being shown at E. Preferably the machine is of that character wherein provision is made to return the reproducer thereof back to its initial position after traversing a record, so that the operation of the apparatus will in the main be automatic. However, inasmuch as phonographs having the characteristic just mentioned are well known to the trade, it is unnecessary to further enlarge upon the details thereof herein, excepting those features which are directly associated with the clock.

F is the reproducer operatively related to the cylindrical record G, rotated through the medium of a spring-motor H having a brake wheel or disk I and coöperating brake-shoe i, carried by a lever i', pivoted intermediate its ends, as at i², and normally held with its shoe i pressed into frictional holding contact with the periphery of the wheel or disk I by a spring i³.

95 Although, as hereinbefore stated, the phonograph-record may be formed to generate music or speech, as may be the wish of the user, the machine is primarily designed to give utterance to the time indicated at various intervals by the hands on the face of the clock. For example, the cylinder may be devoted to twenty-four hours divided into hours and quarters. The means for effecting this actuation of the phonograph simultaneously with the indications by the hands

on the face of the clock may now be pointed out.

Connected to the spring-engaged end of the pivoted brake-lever i' is an elongated vertically-extending straight rod which for convenience in assembling, as also for adjustment purposes, may be made in sections connected by an adjustable coupling j . The lower end of this rod passes through an aperture j' , provided therefor in the horizontal partition D , while the upper end thereof is connected to the outer end of a pivoted detent K , acting as a gravity-pawl and also under the tension of the brake-lever spring i^2 to engage in the notches l of a controller-wheel L , actuated by the ordinary striking-train M of the clock. The inner end or tail of the detent K projects into proximity with a pin-wheel M , mounted on one of the arbors of the clock-train. It is to be noted that the pin-wheel, as also the controller-wheel, have a number of pins and notches, respectively, to correspond to the predetermined intervals at which the phonograph is to operate, four of each being employed herein, representing quarters of an hour.

The operation may now be followed. It being understood that the phonograph-motor is duly wound and that the clock is running, the rotation of the pin-wheel N in the direction of the arrow, Fig. 3, will cause one of the pins thereof to engage the inner end or tail of the pivoted detent K , thereby elevating its tooth out of engagement with the notch of the controller-wheel L and against the tension of the brake-lever spring, which will permit immediate actuation of the clock-train to rotate the controller-wheel, whereby the detent is caused to ride over the periphery thereof until the succeeding notch is presented therebeneath, and during this period the talking-machine will have operated to announce the time, it being remembered that the brake-lever is retracted to free the brake-disk from engagement with the brake-shoe immediately upon the elevation of the detent from engagement with the controller-wheel, as before said.

O is a flat horn for the phonograph of a shape and size to snugly occupy and lie flat within the clockworks-chamber a behind the clock-pendulum. This horn is fitted to an opening in the partition D at its smaller end, from which end a flexible tubing P extends to the reproducer F of the phonograph. It is by means of this flexible tubing that a structure is provided in which the horn may be fixedly mounted as distinguished from the more ordinary machines wherein the horn swings or travels with the reproducer. It also enables the provision of the dust-proof chamber for the talking-machine structure and the compact arrangement of the operating parts, which is quite essential in the mounting

thereof within the limited space afforded by a clock-casing such as herein disclosed.

Having thus described the invention, what is claimed as new, and desired to be secured by Letters Patent, is—

1. In combination with a clock, a talking-machine, and controlling mechanism between the clock and the talking-machine including a brake for the talking-machine, a notched controller-wheel, a detent therefor, and a single means for forcing the detent into engagement with one of the notches of the controller-wheel and for applying the brake. 70

2. In combination with a clock, a talking-machine, and controlling mechanism between the clock and the talking-machine including a brake for the talking-machine, a notched controller-wheel, a detent therefor, and a single spring for forcing the detent into engagement with one of the notches of the controller-wheel and for applying the brake. 80

3. In combination with a clock, a talking-machine, and controlling mechanism between the clock and the talking-machine including a brake for the talking-machine, a notched controller-wheel, a detent therefor, means for normally applying the brake and permitting engagement of the controller-wheel by its detent, and a rod connection between said detent and the talking-machine brake. 90

4. In combination with a clock, a talking-machine, controlling means between the talking-machine and the clock including a brake for the talking-machine, a notched controller-wheel, a detent therefor, means for releasing said detent from engagement with the notched controller-wheel at predetermined intervals and means for simultaneously releasing the brake of the talking-machine. 100

5. In combination with a clock, a talking-machine, controlling means between the talking-machine and the clock including a brake for the talking-machine, a notched controller-wheel, a pivoted detent therefor, means for releasing said detent from engagement with said notched wheel at predetermined intervals, and a connection between said detent and the talking-machine brake. 105

6. In combination with a clock, a talking-machine, controlling means between the talking-machine and the clock including a brake for the talking-machine, a notched controller-wheel, a pivoted detent therefor, means for releasing said detent from engagement with said notched wheel at predetermined intervals and an adjustable connection between said detent and the talking-machine brake. 115

In testimony whereof I affix my signature in presence of two witnesses.

CHARLES C. BISHOP.
